UNITED STATES PATENT OFFICE.

JOHN LA FIELEO, OF PITTSBURG, KANSAS, ASSIGNOR OF TWO-FIFTHS TO J. A. POLLEY,
OF NOWATA, OKLAHOMA.

RAILWAY-GATE OPERATOR.

1,211,321.

Specification of Letters Patent.

Patented Jan. 2, 1917.

Application filed December 29, 1915. Serial No. 69,231.

To all whom it may concern:

Be it known that I, JOHN LA FIELEO, a citizen of the United States, residing at Pittsburg, in the county of Crawford and 5 State of Kansas, have invented new and useful Improvements in Railway-Gate Operators, of which the following is a specification.

This invention relates to improvements in 10 railway gate apparatus and has particular application to train controlled gate mechanism.

In carrying out the present invention, it 15 is my purpose to provide a combination railway crossing gate and cattle guard mechanism wherein the cattle guard will be normally held across the track and the crossing gate held in open position and wherein the cattle guards may be swung to open position 20 and the crossing gate to closed position simultaneously by a car or train when such car or train approaches the crossing, and restored to normal position automatically by the car or train as the latter leaves the 25 vicinity of the gates.

It is also my purpose to provide apparatus of the class described which will operate efficiently and effectively under all conditions and whereby a signal lamp will be 30 illuminated and an audible signal sounded when the crossing gates are closed, thereby notifying pedestrians and the drivers of vehicles approaching the crossing of the condition of the gates.

35 With the above and other objects in view, the invention consists in the construction, combination and arrangement of parts hereinafter set forth in and falling within the scope of the claim.

40 In the accompanying drawings: Figure 1 is a top plan view showing the arrangement of the road gates and cattle gates and controlling devices therefor. Fig. 2 is a longitudinal sectional view through one of the 45 controlling devices. Fig. 3 is a side elevation of the gates showing the relative positions thereof. Fig. 4 is a horizontal sectional view on the line 4—4 of Fig. 3. Fig.

5 is a similar view on the line 5—5 of Fig. 3. Fig. 6 is a transverse sectional view 50 through the roadway showing the connections between the cattle gates. Fig. 7 is a sectional view showing a detail of the invention.

Referring now to the drawings in detail, 55 1 designates a trackway and 2 indicates a roadway intersecting the trackway 1. Arranged upon the trackway 1 at the opposite sides of the roadway 2 are cattle guards A and B respectively. In the present instance, 60 each cattle guard comprises uprights 3, 3 arranged upon opposite sides of the track rails and suitably secured in the earth and intersecting the upper ends of the uprights 3, 3 is a horizontal bar 4. The uprights 65 3 are of a height greater than the height of the train so that the bar 4 will be disposed in a plane above the path of travel of the train, thereby enabling the train to pass under the bar. Arranged between the up- 70 rights 3 adjacent to such uprights are shafts 5, 5 respectively having the upper ends thereof journaled in bearings carried by the bar 4 and the lower extremities journaled in 75 bearings anchored in the earth and secured to the shaft 5 are cattle gates 6, 6 respectively normally arranged end to end and extending across the track rails so as to prevent cattle from traversing the track. Fixed to the lower ends of the shafts 5, 5 are belt 80 pulleys 7 and trained over the belt pulleys is an endless crossed belt 8 whereby motion 85 may be transmitted from one shaft to the other to swing the gates to open and closed positions simultaneously. Also fixed to each shaft 5 adjacent to the lower end thereof is an arm 9 projecting outwardly from the shaft at an angle thereto.

Arranged upon the trackway in advance 90 of the cattle guard A are trips C and D respectively, while disposed in advance of the cattle guard B are trips E and F. The trip D is arranged a suitable distance in advance of the trip C, while the trip E, which corresponds to the trip C, is disposed 95 an appropriate distance in advance of the

trip F, the trip F corresponding to the trip D. In the present instance, each trip comprises a casing 10 sunk in the earth adjacent to the tread side of one line of rails and having the upper end thereof open. Mounted within this casing 10 is a block 11 and interposed between the lower side of the block and the bottom wall of the casing are coiled expansion springs 12 that act to hold the block normally at the upper end of the casing. Secured to the upper surface of the block 11 and projecting upwardly therefrom are short posts 13 terminating in a plane corresponding to the plane of the rail tread and secured to the upper ends of the posts 13 is a curved shoe 14 adapted to be engaged by the flanges of the wheels to depress the block 11 against the action of the springs 12.

10 The trips C and F are arranged adjacent to one line of rails, while the trips D and E are disposed adjacent to the other line of rails and the blocks 11 of the trips C and F are connected respectively with the corresponding arms 9 of the cattle guard gates A and B through the medium of cables 15, while the blocks of the trips D and E are connected to the remaining arms 9 of the gates A and B respectively through the medium of cables 16. The arms 9 connected to the trips C and F are also connected to each other through the medium of a cable 17, while the other arms 9 connected to the trips D and E are interconnected by means of a cable 18. Arranged at opposite sides of the trackway adjacent to one edge of the roadway are vertical shafts 19 journaled in vertically alining bearings carried by suitable supports and secured to each shaft 19 is a road gate 20 normally lying parallel with the roadway and capable of movement across the roadway to close the latter. On the lower ends of the respective shafts 19 are pulleys 21 and trained over these pulleys 21 is an endless crossed belt 22 whereby motion may be transmitted from one shaft to the other to open and close the gates simultaneously. Also secured to each shaft 19 adjacent to the lower end thereof is an outwardly projecting arm 23 and the outer end of the arm 23 is connected with one end of a short cable 24, while the remaining end of such cable is trained over a guide roller 25 and secured to the adjacent cable 17 or 18. Also connected with the outer end of each arm 23 is a cable 26 trained over a guide roller 27 arranged behind the arm 23 and a guide roller 28 arranged in advance of the arm 23 and the cables 26 are connected with the cables 17 and 18 respectively.

15 20 25 30 35 40 45 50 55 60

Normally, the gates of the cattle guards A and B are closed and the gates 20 open so that traffic upon the roadway may cross the track and cattle traversing the roadway

prevented from traveling along the track. 65 When a train approaches the crossing from either direction, such train engages one or the other of the trips C, E, thereby depressing the block 11 against the action of the springs 12 and in the downward movement 70 of the block the cable 15 or 16, as the case may be, is pulled with the effect to rotate the shafts 5 and as all of the shafts 5 are interconnected through the medium of the crossed belts and the cables 17 and 18, all of 75 such shafts are rotated simultaneously to open the cattle guards. In the movement of the cables 17 and 18 to open the cattle guards, the cables 24 are pulled with the effect to swing the arms 23 and rotate the 80 shaft 19 to move the gates 20 across the roadway. After the train has passed the crossing, such train engages one or the other of the trips D, F, according to the direction of travel of the train, thereby pulling the 85 cables 16 or 15 as the case may be to rotate the shafts in the opposite direction to close the cattle guards and in the movement of the cables 17 and 18 under the action of the trip D or F, the cables 26 are pulled and 90 rotate the shafts 19 in the opposite direction to move the gates 20 to open position.

95 100 105 110 115 120

In the present instance, the lower end portion of each shaft 5 and 19 is formed with flat surfaces 29 and bearing upon these flat surfaces is a spring actuated bolt 30 that acts to hold the shafts in operated position, the bolts riding over the flat surfaces of the shafts in the rotation thereof and bearing against such surfaces to maintain the shafts 100 stationary. Each road gate 20 carries a visual signal 31 and an audible signal 32 and these signals are connected in an electric circuit 33 including a suitable source of electrical energy as a battery 34 and a circuit closer 35 under the control of the gate 20 and adapted to be closed when the gate is moved across the road and to be opened when the gate is moved to a position parallel with the roadway.

110 115 120

While I have herein shown and described the preferred form of my invention by way of illustration, I wish it to be understood that I do not limit or confine myself to the precise details of construction herein described and delineated, as modification and variation may be made within the scope of the claim and without departing from the spirit of the invention.

I claim:

In railway cattle guard and roadway apparatus, cattle guards disposed at opposite sides of the roadway and projecting normally across the trackway, road gates arranged at opposite sides of the trackway at 125 one edge of the roadway and normally lying parallel with the roadway and capable of movement across the roadway, shafts car-

rying said guards and gates, pulleys on the lower ends of said shafts, ropes trained over said pulleys whereby all of said gates may be operated simultaneously, train operated trip mechanism for operating said gates, the lower ends of certain of said shafts being squared, and spring actuated bolts engaging the squared portions of said shafts

to hold the shafts against accidental movement.

In testimony whereof I affix my signature in presence of two witnesses.

JOHN LA FIELEO.
